UNITED STATES PATENT OFFICE

HAROLD H. TIMIAN, OF INDIANAPOLIS, INDIANA, ASSIGNOR TO WHEELER-SCHEBLER CARBURETOR CO., OF INDIANAPOLIS, INDIANA, A CORPORATION OF INDIANA

MANIFOLD FOR DOWNDRAFT CARBURETORS

Application filed February 23, 1929. Serial No. 342,098.

This invention relates to an intake manifold system for internal combustion engines and has particular reference to manifolds adapted to cooperate with down draft or inverted carburetors. With such a carburetor arrangement any fuel drippage or condensation is carried into the manifold system and the excess liquid fuel eventually works its way past the pistons to dilute the lubricant in the crankcase of the engine.

It is an object of this invention to provide a manifold drain having an automatic seal or check valve operable when the engine is in use to prevent the suction then existing in the manifold from drawing in air through the drain opening. When the usual accelerating pumps are properly used the engine absorbs the excess fuel produced thereby, but when such pumps are improperly used as by repeated opening of the throttle when the engine is not running, the pumps inject quantities of raw fuel into the manifolding system, causing pools of liquid to collect at low points in the system. Similarly, the improper use of the usual choke or primer will cause a similar collection of liquid fuel in the manifold. The presence of such pools of liquid fuel result in making starting very difficult. It is accordingly an object of this invention to provide means for draining such accumulations of fuel without interfering with the normal operation of the intake manifolding system.

It is another object of this invention to provide an improved manifolding system for down draft carburetors incorporating means assuring a more equal distribution of the heavier liquid particles under both idling and high speed conditions by arranging the branches in such a way that at each point of division the demand on the branches is equal in amount and alternating in phase. To accomplish this result, I provide individual branches for each intake port which unite in pairs and then the paired branches

unite at a common carburetor flange, the points of division having an exhaust jacket or hot spot and the branches sloping downwardly to the ports adjacent which are provided automatic traps and drains for liquid fuel.

Other and further important objects of this invention will be apparent from the disclosures in the specification and the accompanying drawings.

This invention (in a preferred form) is illustrated in the drawings and hereinafter more fully described.

On the drawings:

Figure 1 is an elevation of a manifold embodying the features of this invention.

Figure 2 is a top plan view thereof with the carburetor omitted.

Figure 3 is an elevation thereof with parts broken away to show the branches and exhaust jacket.

Figure 4 is a section on the line IV—IV of Figure 2.

Figure 5 is a section on the line V—V of Figure 2.

Figure 6 is a section corresponding to Figure 5, but showing a modified form of drain valve.

As shown on the drawings:

In Figure 1 the outline of an engine cylinder block is referred to generally by the reference numeral 10. A carburetor 11, of the down draft type, is provided with a mounting flange 12, at its bottom, the usual throttle lever 13, air horn 14 and gasoline inlet connection 15 being shown.

The manifold illustrating one embodiment of this invention has a carburetor mounting flange 16 to which the flange 12 is bolted. The mounting flange 16 is equally divided into two branches by a partition 17, the branches forming relatively short aligned vertical passages 18 and 19, which gradually change from a semi-circular section into a circular section adjacent the points where

each passage connects to two downwardly and oppositely extending individual passages, numbered 20 for the branches from the passage 18 and 21 for those branching from the passage 19. Each of the individual passages 20 and 21 is of uniform slope and terminates in a bend 22 having a connecting passage 23 leading to a mounting flange 24 for attachment to the intake ports formed in the cylinder block. Because the outer passages 20 are longer than the inner ones, their point of juncture is higher than that of the inner passages, as clearly shown in Fig. 4.

In order to drain off accumulations of fuel trapped in the intake manifolding system by interior leakage in the carburetor, improper use of the choke or mixture enriching device, or the usual accumulations of fuel on the walls of the manifold due to a wet mixture; 20 a wall or pocket 25 is formed in the passage 23, and a threaded drain outlet opening 26 is provided in the bottom thereof to receive a passaged nipple 27 to the bottom of which is attached a drain tube 28 which forms part 25 of a collecting manifold 29 having an outlet 29a which may extend to a point of safe disposal. The member 27 is provided with an inverted valve seat 29 and a ball valve 30 is positioned therein and supported by a wire 31 when it drops away from its seat. The ball is light enough to be lifted against its seat by the normal intake manifold suction when the engine is in operation, so that the drain openings are thus closed by the engine 30 suction during the running of engine, but are free to open immediately upon stoppage of the engine to drain off accumulated fuel, the presence of which would make restarting difficult.

40 A manifold form of drain valve is shown in Figure 6 wherein the drain outlet opening 26 is enlarged to form a chamber 32 above a nipple 33 connecting to the drain tube 28. The upper end of the nipple 33 carries a number of short pins 34 supporting a light disc valve 35 which is adapted to be lifted by engine suction to close the outlet 26.

In order to assist in a proper division of liquid fuel and to vaporize a portion thereof, 50 the juncture of the passages 18 and 19 with their branches 21 and 22 is enveloped by a jacket or casing 36 having a flanged opening 37 on the engine side to be bolted to an exhaust manifold.

55 In the operation of the manifold of this invention, the arrangement of individually supplied ports grouped in pairs at each point of division in the manifold with the ports alternating in their charging periods, assures 60 a full and even distribution of the fuel and air mixture to each port regardless of variations in the velocity of flow due to varying throttle openings and engine speeds.

65 The manifold drain arrangement disposes of accumulations of fuel inside the intake

manifold. Such a structure is particularly essential in connection with an overhead or down-draft carburetor, as any fuel leakage or drippage is carried into the manifold and the liquid or unvaporized fuel commonly wetting the walls of the manifold is likewise trapped therein as distinguished from the updraft type of carburetor wherein any such liquid fuel drains back into the carburetor when the engine ceases operation. The manifold drain is provided with a check valve in order to prevent inflow of air to the manifold when the engine is in operation, the drain being open only when the engine has been stopped.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. In an intake manifolding system for internal combustion engines, liquid fuel traps positioned at the low points therein and having drain openings therefrom, collecting means connecting said drain openings and leading to a common point of disposal, and check valves in said drain openings adapted to prevent back flow of air into said manifolding system when the engine is in operation.

2. An intake manifold adapted for use with down draft carburetors, comprising a top inlet connection from the carburetor, downwardly sloping manifold branches of equal pitch leading therefrom, liquid traps formed at the lowermost points in said branches, liquid outlets from said traps, and non-return valves positioned in said outlets.

3. An intake manifold adapted for use with downdraft carburetors, comprising a top inlet connection from the carburetor, downwardly sloping manifold branches leading therefrom, liquid traps formed at the lowermost points in said branches, and drain valves for said traps adapted to close when subjected to suction in said manifold.

4. A manifold adapted to secure uniform mixture distribution from a down draft carburetor, comprising a common inlet having twin branches, downwardly extending twin branches from each original branch, all of said branches having equal drainage angles, individual intake port flanges associated with each of said latter branches, liquid traps at the lowest points in said branches, liquid outlets from said traps, and non-return valves positioned in said outlets.

5. A manifold adapted to secure uniform mixture distribution from a down draft carburetor, comprising a common inlet having twin branches, downwardly extending twin branches from each original branch, indi-

vidual intake port flanges associated with each of said latter branches, liquid traps at the lowest points in said branches, drainage openings from said traps, and check valves in said drain openings adapted to prevent back flow of air into said manifolding system when the engine is in operation.

In testimony whereof I have hereunto subscribed my name at Indianapolis, Marion County, Indiana.

HAROLD H. TIMIAN.
